UNITED STATES PATENT OFFICE.

OTTO BERNZ, OF NEWARK, NEW JERSEY.

PLUMBER'S FURNACE.

Application filed August 26, 1926. Serial No. 131,555.

This invention relates in general to plumber's furnaces and particularly to that type of furnace which includes a tank or reservoir for liquid fuel, such as gasoline, which serves as a base for the furnace and upon which is mounted a fuel pre-heating coil, combustion cup, burner nozzle and top plate or grid above the nozzle adapted to support an article or container to be heated, and a handle for carrying the furnace.

One object of the invention is to provide a furnace of this character embodying novel and improved features of construction whereby the handle may be utilized as a support in conjunction with the grid or top plate for supporting a soldering iron or the like upon the furnace in proper position to be heated, so that the soldering iron or the like may be placed upon the furnace with a minimum of attention and held against accidental displacement by jarring of the furnace or otherwise.

Another object is to provide a furnace of this character embodying novel and improved means for deflecting the heat at the burner nozzle away from the fuel reservoir or tank, said means also serving as a catch basin for any gasoline or the like which may overflow from the combustion cup.

Other objects are to provide in such a furnace novel and improved means for mounting the combustion cup, whereby it may be easily and quickly applied to and removed from a furnace without the necessity of removing nuts, bolts or like fastening members, and to obtain other results and advantages as may be brought out by the following description.

Referring to the accompanying drawings, in which corresponding and like parts are designated throughout the several views by the same reference characters,

Figure 1 is a front elevation of a plumber's furnace embodying the invention;

Figure 2 is a side elevation of the furnace;

Figure 3 is a top plan view of the furnace with portions of the handle and of the tank broken away;

Figure 4 is a longitudinal vertical sectional view through the burner plate, combustion cup and preheating coil;

Figure 5 is a horizontal sectional view, taken on the line 5—5 of Figure 2;

Figure 6 is an enlarged fragmentary vertical sectional view through the base plate and the end of one of the standards for supporting the combustion cup and burner plate upon the tank;

Figure 7 is a top plan view of the base plate, and

Figure 8 is an enlarged fragmentary transverse sectional view through the connection of the fuel pipe to the tank.

Specifically describing the illustrated embodiment of the invention, the furnace comprises a tank or reservoir A which serves as a base for the furnace and from the top of which extend vertical rods or standards B to the top of which is secured as by nuts C a top plate or grid D. Beneath the top plate D is mounted a combustion cup E within which is arranged a pre-heating coil F to one end of which is connected a burner nozzle G, the other end of said pre-heating coil being connected by a fuel pipe H through a valve I to the top of the tank A. The tank is provided with a filling opening K and an air pump L by means of which the fuel is forced through the fuel pipe H and the pre-heating coil F. The general combination of the parts above described is known in the art and no claim to novelty is made thereon.

In accordance with the invention, the top plate D is provided with a pair of diametrically opposite pivot studs 1 to which the arms of a U-shaped handle 2 are pivotally connected intermediate their ends so that said handle may be swung upwardly above the top plate for carrying the furnace or downwardly to one side of the furnace into an out-of-the-way position when the furnace is in use. The extremities of the ends of the handle are provided with inturned fingers or projections 3 so arranged as to engage the under side of the top plate D when the handle 2 is swung in one direction so that movement of the handle in said direction is limited and the handle held in an inclined relation to the top plate, as shown in Figures 2 and 3 of the drawings. When the handle is in this position, it serves in connection

with the top plate as a support for a soldering iron or the like ¹⁰ O, shown by dot and dash lines in Figure 2. When the handle is swung in the direction opposite to that shown in Figure 2 the inturned fingers 3 clear the top plate and permit the handle to swing downwardly against the side of the tank A, as shown by dotted lines in Figure 2.

Upon one of the vertical rods or standards 10 B is adjustably mounted a dished plate 4 which may be formed of sheet metal and has at one side an eye 5 loosely slidable upon said one of the rods B and in which is fitted a set screw 6 for clamping the eye fast to the 15 rod. Upon this plate 4 is supported the combustion cup E, and the upper end of said combustion cup is provided with a plurality of longitudinally extending projections 7 which loosely enter corresponding 20 openings 8 in the top plate D.

As above stated, the preheating coil F is arranged within the combustion cup E, and the combustion cup is held in proper relation to the pre-heating coil by the plate 25 4 and the projections 7. To remove the combustion cup E it is merely necessary to lower the plate 4 by loosening the set screw 6, which permits the combustion cup to move away from the top plate so that the projections 30 7 are withdrawn from the openings 8, whereupon the combustion cup may be moved laterally from beneath the top plate. In some instances the burner nozzle G is made removable without disturbing the 35 combustion cup and pre-heating coil, as shown in the drawings, the nozzle projecting from one of the air openings of the combustion cup so as to be accessible from the outside of the cup. Accordingly, it is necessary 40 to remove this burner nozzle before the combustion cup can be removed, as above described.

In addition to serving as a support for the combustion cup, the plate 4 also catches 45 any fuel which overflows from the pre-heating coil so as to prevent the fuel from falling onto the tank, becoming ignited thereon and producing heat which might result in an explosion of the tank. Also, the plate 4 serves to deflect the heat from the combustion cup and the burner nozzle away from the tank to prevent undue heating of the latter.

The pre-heating coil F is carried by the 55 fuel pipe H and said fuel pipe is separable from the furnace to permit cleaning or renewing of the pre-heating coil. It is desirable to make the connection and disconnection of the fuel pipe as simple as possible and with the least number of threaded joints. Accordingly, I have shown the valve I as having an exteriorly threaded outlet nipple 9 having a smooth end 10, and the fuel pipe has fixedly secured thereto a collar 11 to fit tightly against the smooth end

10 of the nipple 9. A flanged nut or union 12 is loosely rotatable and longitudinally slidable upon the fuel pipe and is threaded to engage the threaded nipple 9 so as to clamp the collar 11 tightly against the nipple, as clearly shown in Figure 8 of the drawings. Preferably the fuel pipe has a reduced end 13 to accurately fit a corresponding recess 14 in the nipple 9. To connect or disconnect the fuel pipe to the valve, 75 it is merely necessary to unscrew the nut or union 12, and the connection involves only one threaded joint, that is, between the nut and the nipple.

It is desirable to have as few openings as 80 possible in the fuel tank, and accordingly I form the base plate 15 which serves as a connection between the rods B and the tank, of one piece of malleable iron which has integral threaded bosses 16 to receive the 85 threaded ends 17 of the rods B. The plate 15 is brazed to the top of the tank A so that all rivets and consequent openings are eliminated as well as solder, which is sometimes used and is objectionable as being too susceptible to heat.

While I have shown and described the furnace as embodying certain details of construction and have shown the invention embodied in a certain type of furnace, it will 95 be understood that the details may be modified and changed and the invention embodied in other types of furnaces by those skilled in the art without departing from the spirit or scope of the invention. Therefore, I do not desire to be understood as limiting myself except as required by the following claims when construed in the light of the prior art.

Having thus described the invention, what 105 I claim is:

1. In a furnace, the combination of a frame, a burner thereon, a top plate disposed over said burner and formed at its edges with diametrically opposite pivot 110 studs, and a U-shaped handle having its arms pivotally mounted intermediate their lengths upon said pivot studs, the free ends of said arms of the handle being formed with inturned fingers, and said studs, in-turned fingers and top plate being relatively arranged so that said fingers engage the underside of said top plate in spaced relation to said pivot studs when the handle is swung in one direction to hold said handle 115 in inclined relation to said top plate above the latter to support a soldering iron or the like, and said handle may swing in the opposite direction downwardly into an out-of-the-way position at one side of said frame.

2. In a furnace, the combination of a base, a burner, a fuel preheating coil, a top plate over said burner, a standard for supporting said top plate upon said base, a cup beneath said preheating coil, a dished plate mounted

to move up and down upon said standard to support said cup and catch fuel which overflows from said cup, and means for fastening said plate against movement on said standard.

3. In a furnace, the combination of a base, a burner, a fuel preheating coil, a combustion cup around said preheating coil having a projection thereon, a top plate above said burner having an opening to loosely receive

said projection upon movement of said cup toward said plate, a standard for supporting said top plate upon said base, a plate mounted to move up and down upon said standard and underlying said cup to support the same with said projection in said opening in the top plate, and means for fastening said plate against movement on said standard. 15

OTTO BERNZ.
